MEANS FOR HEADWEAR MANUFACTURE

Filed Oct. 3, 1938

FIG. 1.

FIG. 2.

UNITED STATES PATENT OFFICE

2,207,910

MEANS FOR HEADWEAR MANUFACTURE

Alexander Campa, St. Louis, Mo., assignor to
 Caradine Hat Company, St. Louis, Mo., a corporation of Missouri

Application October 3, 1938, Serial No. 232,996

1 Claim. (Cl. 223—14)

This invention relates generally to the manufacture of hats or headwear. More particularly, my present invention has to do with a certain new and useful improvement in the brim of a hat formed of a fabricated body and to the method and means of constructing the same.

Such a hat-body is constructed by weaving or pleating collodion-coated strands of paper, fiber, or suitable straw and in its original condition embodies an excessively wide brim, is soft and pliable, and is unsightly and unshapely in appearance, merely approximately conforming to the shape and contour of the finished hat.

In block-shaping and otherwise processing hat-bodies of this type, means must be employed to produce a hat of shape and contour conforming in style to prevailing fashions, which at present dictate a rather wide brim having a downward curl at the front and an upward curl at the rear. The depth of this curl, as indicated at *x* in Figure 1, is commonly referred to as the flange; thus, for instance, if the distance *x* is one inch, the particular hat would be said to have a brim of one inch flange.

Now United States Letters Patent No. 2,040,354, issued on May 22, 1936, fully describes and sets forth methods and means for the production, from a raw hat-body of the type mentioned, of a finished hat having a welted brim of relatively small flange, such, for instance, as a $\frac{3}{8}$ or $\frac{1}{2}$ inch.

The equipment for brim production described in said Patent No. 2,040,354, while entirely successful in the formation of an attractive brim of small flange, could not successfully effect the making of an equally attractive brim of relatively deep flange; on the contrary, a brim having a number of radial creases or so-called puckers at various spaced points around the margin resulted, rendering the hat unmerchantable.

In addition, welted brims are of two types, namely, "upper" welts in which the in-turned brim margin is folded upon the upwardly presented brim face, and "under" welts in which the in-turned brim margin is folded upon the downwardly presented brim face. At the present time, so far as I am aware, entirely different means must be employed for the production of these two types of welted brims.

My invention hence has for its object the production in a simple, economical, and convenient manner upon a hat of the type stated of an attractive, smooth, welted brim having a substantially long radius of curvature or "deep flange."

My invention also has for an object the provision of a process and means for producing attrac-

tive unpuckered hat brims either of "upper" or of "under" welt type in a simple, convenient manner and without material change in operation or equipment.

And with the above and other objects in view, my invention resides in the novel features of form, construction, arrangement, combination of parts and in the method or process presently described and pointed out in the claim.

In the accompanying drawing—

Figure 1 is a side elevational view of a finished hat having a deep-flange brim constructed in accordance with my present invention;

Figure 2 is a schematic view illustrating the several sequential steps in the production of a broad or wide deep-flange brim in accordance with my present invention;

Figure 3 is a vertical sectional view of an initial blocking or forming machine for processing the raw hat-body and its brim, in accordance with my present invention;

Figures 4 and 5 are, respectively, perspective views of the co-operable male and female brim-formers of my invention;

Figures 6 and 7 are longitudinal and transverse cross-sectional views, respectively, of a hat-body during brim formation between co-operable male and female formers of my invention; and

Figure 8 is a fragmentary vertical sectional view of co-operable male and female brim formers in which the female member is modified for the production either of "under" or "upper" welts.

Broadly speaking, the production according to my invention of a finished hat A, Figure 1, having a wide, deep-flange brim B comprises, in sequential order, the steps of initial blocking, initial sizing, brim-forming, brim stitching and trimming, second sizing, and final blocking, as indicated in Figure 2 and as will presently be more fully described.

In the initial blocking, the raw hat body A' is placed between preferably steam-heated, pressure-expansive companion mold-members F, F', constructed of vulcanized rubber and having a shape conforming substantially to the desired shape of the entire finished hat A, both the crown and brim of the hat being thus formed or shaped in one operation.

After blocking, the hat-body A' is initially sized, preferably through application, by spraying, dipping, or other suitable method, of a coat of suitable hat lacquer to the brim and lower portion of the crown.

Upon application of the initial sizing coat, the hat-body A' is allowed to dry and is then sequen-

tially subjected to a brim-forming operation in which I employ a male brim-former C comprising a somewhat elliptically contoured preferably metallic ring 1 dished in cross-section and accurately machined upon its one or under face, as at c, to conform in curvature precisely to the brim-shape of the initial shaping pressure-expansive formers or molds F, F", the former C being of substantial thickness, as shown, and provided upon its other or upper face with a marginal-pressing-rim c'.

Fixed to the ring 1 along its inner peripheral margin by means of screws or the like 2 and presented outwardly from the central portion of the under face c thereof, is a preferably wooden block 3 having a peripheral shape and contour conforming to the inner contour of the crown adjacent the brim of the particular hat-body, as best seen in Figure 3.

Also provided for complementary engagement with the male brim-former C, is a preferably metallic female brim former D having an elliptically shaped opening, as at 4, and an upper face d precisely contoured for exact conformation to block 3 and to the under face c of the male brim former C, and a flat under face d' suitable for resting securely upon the usual work table E.

The former D, between the outer margin of its brim forming face d and its vertical side face d', is sharply chamfered in the provision of a bevel d², which is equipped with a pair of diametrically opposed index lines 5, 5', for registration with similarly disposed index lines 6, 6', upon the pressing margin or rim c' of the male brim former C.

After the initially sized hat-body, as A', Figures 5, 6, has dried sufficiently, the crown i thereof is pressed downwardly upon the shallow crown block 3 of the male brim former C and the hat-body A and brim-former C together forced downwardly into the female brim-former D, as best seen in Figure 5, whereupon the brim, as B', will be formed under pressure between the brim-forming surfaces c, d, of the formers C and D, respectively. Any excess marginal portion, as b², of the brim B' will project outwardly from between the formers C and D and is then manually turned inwardly and pressed with a hot iron or the like G upon the pressing margin or rim c', in the formation of an "under" welt, also as best seen in Figures 5 and 6.

For the formation of an "upper" welt, a female

member D' may be provided having a curved brim-forming surface e complementary in shape to the surface c of the male member C and having an inwardly sloping vertical side face e' against which the extended brim margin b² may be folded down and pressed, all as best seen in Figure 8.

Following such blocking operation, the hat-body A' is removed from the brim-forming members C and D and the brim B' thereof stitched and trimmed preferably as in said Patent No. 2,040,354 set forth. Preferably also the entire hat-body A' is sprayed, coated, and worked as indicated in Figure 2 and as in said Patent No. 2,040,354 also fully described in the production of the finished hat A having an exceedingly attractive, neat, welt-edge brim B having, in turn, a curl or flange of selected depth and flexibility to meet the demands of present day fashions and requirements.

Preferably, the former-block 3 is provided with a plurality of finger-grip recesses f for facilitating hat-forming operations, and it should be understood that the degree of curvature of the co-operably brim-engaging faces of the formers C and D may be varied to meet the selected flange-depth of the finished brim, and that other changes and modifications in the several steps of brim-production, as well as also in the form, construction, arrangement, and combination of the several parts of the hat may be made and substituted for those herein shown and described without departing from the nature and principle of my invention.

Having thus described my invention, what I claim and desire to secure by Letters Patent is:

A brim former for woven strand hats comprising, in combination, a first ring-shaped member having a crown-accommodating opening, the rim of said opening having a concaved upper face, a vertical peripheral side wall, a flat under face for support engagement, and a beveled face intermediate of, and connecting, said upper face and peripheral wall, and a companion ring-shaped member having an under face convexed for precisely matching the concaved upper face of the first member, and a block adapted for projection through the ring of the first member for crown-engagement, the second member terminating in a flat marginal pressing rim and registering marginally with the first member when the members are in brim-pressing engagement.

ALEXANDER CAMPA.
